CHECK WRITING MACHINE

Pliny Catucci, Newark, N. J.

Application October 19, 1932, Serial No. 638,455

15 Claims. (Cl. 101—19)

Check writing machines are generally of two classes, one of which uses an independently rotatable type wheel which is manipulated to form a printing line representing the amount to be written on a check or the like. The other class employs a plurality of type bearing bars mounted for longitudinal shifting movement, which movement is normal to the line of printing, the bars being moved into selective registration to form a printing line representing the amount to be written on the check. The latter class of check writing machine is generally preferred and has been found to be more efficient than the machine employing the rotatable type wheel.

15 It is an object of my invention to overcome objections to the inefficiency of the inking mechanism generally used with machines of the class employing straight type bearing bars, by providing an inking mechanism having an absolutely uniform and unfailing action, which enables the production of clear and perfectly inked numerals on checks or commercial paper and which mechanism enables the writing of a very large number of checks before re-inking is necessary.

20 My inking mechanism includes an inking element controlled by a predetermined resilient pressure, which insures the spreading of the proper amount of ink over the type at each print without unnecessary waste of ink.

25 A further object is the provision of a check writing machine having a simple and novel mechanism by which is effectively controlled the successive movements necessary for inking the characters on a printing line, scarifying the name of the payee, and pressing the printed character into the body of the paper. The three steps, inking, scarifying, and printing, are each independently controlled and follow one another in point of time, thus distributing the working strain 30 throughout the entire cycle and enabling the machine to be operated smoothly by exerting a light force upon an operating handle.

35 A further object is the provision of novel means of obtaining perfect horizontal alinement of the type bearing bars by placing the resting point which receives the printing pressure, closely adjacent the face of the type. This feature prevents the tilting of the type bar and consequent poor alinement and printing. My expedient insures the faces of the types being exactly on a common plane, which is essential for the uniform printing of the entire face of each character.

40 Another object is to provide a simple pawl and ratchet mechanism which insures the smooth operation and proper registering of the type-bearing bars, regardless of the direction in which the bars may be moved. This feature obviates the necessity of error keys, and enables rapid operation of the machine.

45 The free registering end of the pawl is pushed

upward by a spring with a thrust sufficient to balance the weight of the type bar, which in turn is free to move in either direction and is always ready to snap into place to register on the line of printing. This construction prevents the type bearing bars, when carelessly manipulated, from being out of alinement by stopping midway between characters. Another object is the provision of a serrated printing platen mounted to freely rock to allow the serrations thereon to seat themselves in mesh with the serrations on the type characters on the line of printing. This enables every point of the respective serrated surfaces to be in proper pressing contact so that the ink in the serrations is spread evenly over every point of the printed figures.

50 A further object is the provision of a simple gauge for accurately alining a check, the gauge being readily adjustable and preventing the check from being displaced out of line when printing takes place, the printing being at all times parallel with the lines on the check.

55 A further object is the provision of means for readily indicating the position of the line of printing on a check, this means comprising a pointer which bears lightly on the check and offers no resistance to the upward movement of the check to cause creasing or marring.

Another object of the invention is to provide 30 simple and novel means for firmly clamping certain parts of the machine in a manner to enable the exerting of a powerful clamping action evenly distributed cross-wise of the machine, which in turn offers an even resistance to pressure on the entire printing line.

35 A further object is the provision of a scarifying device comprising an upper female matrix having a plurality of parallel grooves and a lower male matrix having a plurality of spaced parallel rows of sharp pyramids registering with the grooves in the female matrix to enable the latter to be adjusted longitudinally relative to the machine without interfering with proper scarifying action.

40 These and other advantageous objects, which will later appear, are accomplished by the simple and practical construction and arrangement of parts hereinafter described and exhibited in the accompanying drawings, forming part hereof, and in which:

45 Fig. 1 is a plan view of my check writing machine,

50 Fig. 2 is a side elevational view of the machine,

55 Fig. 3 is a plan view of the machine with the cover removed,

55 Fig. 4 is a bottom view of the upper part of the machine showing the arrangement of the type bars thereon,

60 Fig. 5 is a perspective view of spacing bars employed to space and support the type bar,

Fig. 6 is a perspective view showing a detail of a pawl and ratchet device used with the type bars,

Fig. 7 is a perspective view of a scarifying device, showing the method of adjustably mounting the same,

Fig. 8 is a sectional view of the machine at rest, that is, before manipulating the handle to operate the same,

10 Fig. 9 is a sectional view showing the position of the inking device and matrices at the beginning of the cycle of operations for printing characters on a check,

15 Fig. 10 is a sectional view showing the next step in the printing operation, the inking rollers being moved out of the way and the matrices being forced upwardly to perforate and print characters on a check,

20 Fig. 11 is a sectional view showing details of the mechanism when the machine is at rest,

25 Figs. 12, 13, 14 and 15, show positions assumed by a lost motion device used in the mechanism for controlling the position of the inking rollers during a cycle of operation,

30 Figs. 16, 17, and 18, are plan views of the machine showing the positions assumed by a second lost motion device used in the control of the inking mechanism, during a one-half cycle of operation, and

35 Figs. 19 and 20 show details of and positions assumed by a latching device for clamping the two main parts of the machine together during operation,

Fig. 21 is a plan view of check guides used on the machine, and

Fig. 22 is a perspective view of an adjustable frame for supporting a scarifying device.

Referring to Figs. 1 and 2, the machine is shown to include a lower casing 1, to which are 40 pivotally connected links 2, the latter being attached to an upper casing 3. The lower casing 1 is supported by four feet 4, preferably made of rubber or a similar material, and extending through the side walls of the casing is a shaft 5, having detachably connected thereto an operating crank 6. Before operating the machine, the casings are clamped to each other by pressing down on a handle 7, which controls a latching device hereinafter described.

50 Mounted on the upper side edge of the casing 1, is a metal guide strip 8 which supports a pair of spaced check guides 9 and 10, which are transverse to strip 8 and slidable thereon.

Attached to the side of casing 3 is a small plate 11 having a pair of spaced ears 12 which serve as stops for an arm 13 projecting upwardly from a downwardly directed arm 14 pivoted at 55 to the plate 11. The lower end of arm 14 is positioned so that it will be slightly above a check between the guides 9 and 10, and the arm 14 has its lower extremity bent to provide a lip 16 transverse to the guide strip 8 and to indicate the line of printing of the machine, thus enabling ready adjusting of a check in the guides 9 and 60 10 so that the printing may be on any desired line on the check.

70 The upper plate 47 of casing 3 has a plurality of longitudinal slots 18 in which move arms 19 with knobs 20 attached thereto. The arms 19 are connected to the type bars, hereinafter described, and by moving the arms 19 in the slots, the machine can be set to print desired amounts on a check, and moving in a slot 21 is a knob 22 75 connected to a device, hereinafter described, for

resetting the type bars to their initial position to enable the setting of the machine to write a different amount.

Referring to Fig. 4 there is shown the under-side of casing 3 having mounted thereon a plurality of metal spacing strips 23, (see Fig. 5) 5 each of which has attached thereto a transverse flange 24, fitting in grooves in the lower portion of type bars 25, which have type 26 attached to the under-side thereof, (see Fig. 6). The flanges 10 24 provide guiding and supporting means for the type bars at a point as near the type as practicable, and thus prevent tilting of the type bars and uneven printing of the type.

As is shown in Fig. 4, the plurality of type bars 15 25 are spaced from each other and guided by the strips 23; and each type bar has a longitudinal groove in which moves a pawl 27 engaging ratchet teeth 28 formed on the type bar. The pawl 27 is in the form of a small roller mounted on the 20 end of an arm 29, of a rocker which is pivotally mounted on a shaft 30 supported by the side walls of casing 3. The rocker has a short depending arm 31 which abuts one end of a small compression spring 32, the other end of the spring 25 abutting a bracket 33. It will be seen that the thrust of spring 32 maintains the pawl in engagement with the ratchet 28 and prevents accidental slipping of the type bar regardless of its position. The spring exerts a thrust substantially equal to the weight of the type bar.

The spacing strips 23 are maintained in relative positions by transverse spacing plates 34, 35 attached thereto.

The symbols, 36, 37, "DOL'S" and "CTS" are 35 permanently mounted, and a detachable plate 38 bearing the name of the proprietor, organization or the like is held in position by a detent 39 resting in a notch in the plate 38, the detent 39 being attached to a lever 40 normally urged by a coiled 40 spring to hold the detent in the notch.

Referring to Fig. 16, there is shown a plan view of the lower casing 1, with the upper casing 3 removed. Mounted on the inner side walls of casing 1 are a pair of channel guides 41, in which move rollers 42 rotatably mounted on a plate 43, the latter having also attached thereto a pair of leaf spring fingers 44, and upturned lugs 44', which frictionally engage the sides and upper walls of guides 41 to prevent accidental movement of the plate 43.

Carried by the plate is an ink trough 45 in which are rotatably mounted three ink rollers 46, 47 and 48. The roller 46 is slightly higher than rollers 47, 48 and directly engages the type 55 26 on the type bars, while the rollers 47 and 48 serve as reservoirs to maintain roller 46 properly inked.

Attached to plate 43 is a metal plate 49 having an angle shaped cam slot 50 in which moves a roller 51 mounted on an arm 52 fixed to the upper end of a vertical shaft 53, the lower end of the shaft having fixed thereto an arm 54 pivoted to a transverse arm 55 integral with a bar 56, which has a forked extremity 57 and 58 embracing the shaft 5, (see Fig. 11).

The fork 57 has a block 59 attached to the end thereof, and a second block 60 is fixed to the bar 56 and slightly spaced from block 59, while on fork 58 is a stop pin 61. Fixed to shaft 5 (see 70 Figs. 12, 13, 14 and 15) is an arm 62 having a pin 63 projecting therefrom. As the arm 62 is rotated clockwise the pin engages the surface 64 of block 60 to move the bar rearwardly to rotate shaft 53 to cause roller 51 to move in the cam 75

slot 50 to draw the plate 43 back towards the shaft 53. Movement of the plate 43 continues until the peak 130 of the angle cam slot 50 has been passed. Thereafter, further movement of 5 arm roller 51 in the same direction in the slot 50 has no effect upon the plate 43, and movement of the latter ceases.

When shaft 5 and arm 62 are rotated counter-clockwise, (Fig. 15) the pin 63 does not engage 10 block 60 and has no effect on the bar 56 until it engages block 59, when it will move the bar 56 to the left (see Figs. 11, 12, 13, 14 and 15) to move the roller 51 in the opposite direction in the cam slot 50 to return the plate 43 to its 15 original position. The structure above described enables the proper timing of the inking mechanism movements so that it will not interfere with the printing operations, at the same time enabling the machine to be operated by a simple 20 forward and back movement of the crank 6. It will be seen that the considerable lost motion inherent in the forked bar 56 and the cam slot 59, prevents return of the inking mechanism to inking position before the printing parts are out 25 of the way.

Supported by the side walls of the casing 1 is a pin 65 which pivotally supports one end of a U-shaped frame 66, the legs 67 of which carry, at 30 their extremities, the rollers 68 engaging the cams 69 fixed to the shaft 5, (see Fig. 3). Supported by the legs 67 is a pin 70 having rotatably mounted thereon the arms 71 of a bracket 72, which has a vertical plate 73 arranged to engage the underside of the ink trough 45. A cross-bar 74 (see Fig. 10) is fixed to the legs 67 and supports a compression spring 75 of predetermined strength, the spring bearing against the bracket 72, so that when the vertical plate 73 bears against the trough 45, the latter will 40 move upward to cause the roll 46 to apply ink to the type 26 with a pressure which cannot exceed the strength of the spring. In this manner, uniform inking is assured, and there is no wasting of ink because of varying pressures.

45 Fixed to the shaft 5 are a pair of arms 76 pivotally connected to links 77, which are rotatable on a shaft 78, the latter being supported by a pair of arms 79 rotatably mounted on a shaft 80 supported by the side walls of the casing 1. The shaft 78 bears against the underside of a cross-plate 81 connecting the side arms 82 of a frame 50 pivotally mounted on shaft 83.

The cross plate 81 has mounted thereon an 55 upstanding plate 84 to which is adjustably attached, by means of rivets and slots, a plate 85 having its lower portion bent to provide a shoulder 86 engaging a set screw 87 threadedly mounted in the plate 81. The bottom of the casing has an aperture 88 to enable access to the set screw for the purpose of adjusting the plate 85. The 60 upper edge of plate 85 supports a platen bar 89 having its upper surface provided with a plurality of parallel rows of spaced pointed small pyramids. The underside of the scarifying bar 89 has a groove slightly wider than the plate 85 so that the bar 89 can have a slight rocking movement thereon, similar to the mounting of the platen bar 100, which has a groove 103 wider than the plate 91, (see Fig. 7). Bar 100 has a bayonet slot 104 which cooperates with a pin 102 on the plate 91, (see Fig. 7) and the bar 89 has a 65 similar mounting and connection on the plate 85.

An upstanding plate 90 has adjustably connected thereto the plate 91, having its lower end

bent to provide a shoulder 92 engaging an adjusting screw 93 which can be manipulated through the aperture 88. The plate 90 is connected to the side arms 94 pivotally mounted on a pin 95 supported by the walls of the casing. 5 The pin 95 passes through elongated slots 96 in the arms 94 to enable the latter to be adjusted by means of an adjusting screw 99 engaging a cross bar 97 connected with the side arms 94, said screw 99 being supported by a bracket 98 10 pivotally mounted on the pin 95. As above described, the platen bar 100 is rockably mounted on the plate 91, said bar having its upper surface serrated as shown at 108.

The arms 94 are pivotally secured to a pair 15 of links 104 which are pivotally mounted on the shaft 78.

The scarifying bar 89 is arranged to cooperate with an upper matrix plate 105 having a plurality of grooves 106 registering with the spaced rows 20 of small pyramids 107 on the bar 89, the plate 105 contacting the edges of spacers 23 and being spaced from the type 26, the latter having a serrated surface. The plate 105 is supported by a bar 109 which is slidably mounted on a frame 25 110 to which is attached a spring 111, also connected to the sliding bar 109 to normally urge the plate 105 to a predetermined position. A screw 112 enables adjustment of the normal position of plate 105, and a screw 113 limits movement of the bar in one direction. The sliding bar 109 has an arm 114 connected thereto and carrying a roller 115 which engages an upstanding arm 116 attached to the plate 43. When the plate 43 moves to the left (see Fig. 11), the arm 116 engages the roller 115 to move the matrix plate 105 30 back out of the way of the inking roller.

For proper operation of my machine it is essential that the upper casing 3 be tightly clamped to the lower casing 1. For this purpose, I provide a novel latching device (see Figs. 19 and 20) which comprises a ledge 117 mounted on the lower casing, and a hasp 119 having a central opening in which is positioned a circular disc 120 eccentrically mounted on a squared shaft 121. 45 On each side of the hasp and disc are plates 122 through which the shaft passes also. The plates 122 carry a pin 123 which, in one direction of movement, engages the hasp 119 to limit rotation of the disc 120 and plates. In operation, 50 when the handle 7 is forced downward, the eccentric disc 120 and the hasp move together until the hasp engages the ledge 117, at which time the disc continues to rotate, but, rotary motion of the hasp being arrested, the eccentric action of 55 the disc causes an upward movement of the hasp against the under side of the ledge, and thus provides a very tight latching of the two casings. Rotary movement of the disc 120 is limited by engagement of the pin 123 with the hasp in one 60 direction; or by engagement with a projection 124 on the hasp in the opposite direction.

In operation, the upper casing 3 is tightly clamped to the lower casing 1. The type is then set to the desired amount by manipulating the 65 type bars 25 by means of the knobs 20.

A check is then inserted between the guides 9, 10, which are adjusted until the indicator 16 is directly over the line upon the check where it is desired to print the set amount. The parts are 70 now in the positions shown in Fig. 8, with the inking roller directly beneath the type. The crank 6 is then rotated towards the latch handle 7, to rotate the shaft 5. At the beginning of the movement, the cam 69 engages the roller 68 to 75

bring the plate 73 in contact with the ink trough 45 to raise the latter to bring the roller 46 into engagement with the type. In the meantime, due to the lost motion structures in connection with the forked bar 56 and cam slot 50, the plate 43 is stationary, and the upstanding plate 116 maintains the matrix plate 105 out of the way.

Further movement of shaft 5, causes the plate 43 to move to the right, (Fig. 9) drawing the roller 46 over the type to insure complete and uniform inking. As the plate 43 moves to the right, carrying with it the inking trough and rollers, spring 111 urges the matrix plate 105 in the same direction until it reaches the position shown in Fig. 10.

In the meantime, rotation of shaft 5 is causing the bars 89 and 100 to move upward. The bar 89 rises first, as shown in Fig. 9, and then bar 100 reaches its upward position to press the check 20 tightly against the type 26. The type 26 is serrated and cooperates with the serrations 108 on the bar 100 to provide a proper impression, the bar 100 having a slight rocking and longitudinal movement to assure registration of the serrations 25 on the type and the bar. The bar 89 is being pressed upward to perforate the paper over the name of the payee. Near the completion of the up movement of bar 89, it is given a final upward thrust by the lowered portion 118 of the plate 30 81 passing over the shaft 18. The small sharp pyramids 107 on the upper surface of bar 89 register with the grooves in the plate 105 to pierce the paper. The grooves 106 are of considerable length to enable proper registration to 35 accommodate various adjustments of the plate.

During the above movements of the bars 89 and 100, the plate 43 is stationary. Upon the reverse movement of crank 6 and shaft 5, the bars 89 and 100 first begin to descend, and then the plate 43 and inking mechanism returns to its initial position.

The machine may be cleared by moving the finger piece 22 in the slot 21. The finger piece 22 is attached to a bar 125 extending along a side wall of the upper casing 3 and bearing on rollers 126 mounted on the side wall; and fixed to the bar 125 is a transverse cross-bar 127 carrying a roller 128 which rides on one of the spacing strips 23. In clearing the machine, the cross-bar 127 is moved to engage the ends 129 (see Fig. 9) of the type bars to force them to their initial positions.

From the above description it will be seen that I have provided an effective check writing machine in which complete and uniform inking of the type is insured, the type making an even and uniform impression, and proper operation of the perforator or scarifier and other parts of the machine is certain at all times. My mechanism enables extended use of the machine without reinking of the rollers, and the pressure on the type is through the paper, producing a positive scarifying action.

It will be noted that in the inking of the printing characters immediately preceding the printing of the characters on a check, the ink trough 45 is pressed upwardly by the plate 73, which acts through the check 140, see Fig. 9. By acting directly through the check, the structure is greatly simplified, and the check is in no way marred or mutilated.

Checks are inserted into my machine from the sides, and are guided by the channel guides 9, 10, which extend across the machine and are adjustably mounted on the guide strip 8, which extends

the length of the machine. The guides 9, 10 are provided with leaf springs 141 which frictionally grip the strip 8 to hold the guides in adjusted positions. (See Fig. 3.) It is obvious that my arrangement enables the printing of amounts on checks of all sizes, and on various sizes of commercial papers, which heretofore could not be fitted to a check writing machine. The guides 9, 10 can be adjusted for handling paper the length of the machine, and when it is desired to print on a larger sheet of paper, the upper casing 3 can be raised to insert the paper. The upward movement of guide 9 and the downward movement of guide 10 are limited by a pin 142 projecting from the side of the guide strip 8.

In my latching device, (see Figs. 19, 20) in order to prevent the hasp from swinging too far to the right when the upper casing 3 is raised, I provide a stop 143, which engages the hasp and maintains the hasp in proper position to engage the ledge 20 147 when the upper casing is lowered.

The upper casing 3 of the machine is inclined, and after the knob 22 has been moved upwardly in its slot 21 to clear the machine, it falls back by gravity to its normal out-of-the-way position. My clearing device is very simple in structure and positive and rapid in operation. It should, also, be noted that should one type bar be erroneously set, it is not necessary to clear the entire machine to correct the error as is the case with other check writing machines. Since the type bars can be moved freely up or down, it is only necessary to manipulate the particular type bar which may be in error.

The latch shown in Figs. 19, 20, is mounted in the center of one end of casings 1 and 3. This mounting of the latch, together with the two links 2, which hingedly connect the casings together, provide a three-point clamping arrangement, which equally distributes the forces transversely over the casings.

In order to accommodate various spacings between lines on a check, that is the spacing between the line bearing the name of a payee, and the line bearing the amount of the check, I have provided means for adjusting the distance between the scarifying bar 89 and the platen bar 100. The platen bar 100 may be adjusted as has already been explained.

As shown in Figs 10 and 22, the ends of the arms 82 of the frame, which supports the scarifying bar 89, are pivotally mounted on the shaft 83 and supported by the arms 160 of the adjustable frame 161, which is pivotally mounted upon the shaft 95. The arms 160 of the adjustable frame 161 are connected by a cross bar 145, the center portion of which is apertured to receive a threaded nut and threaded bolt, 146, the threaded nut being surrounded by a coiled spring 147 which abuts against the cross bar 145 and a plate 60 148 fixed to the rear of the lower casing.

The bolt 146 has a rounded head 149 movable in and slightly larger than an elongated slot in the plate 148. By adjusting the bolt 146, the arms 82 may be brought forward or backward, and thereby regulate the distance between the bar 89 and bar 100, the rounded head 149 of the bolt canting in plate 148.

The foregoing disclosure is to be regarded as descriptive and illustrative only, and not as restrictive or limitative of the invention, of which obviously an embodiment may be constructed including many modifications without departing from the general scope herein indicated and denoted in the appended claims.

Having thus described my invention, what I claim as new and desire to secure by Letters Patent, is:

1. In a check writer, a type bar having printing characters on one side thereof, a platen bar, means to cause said bar to press a check into printing engagement with one of the printing characters, an inking roller to ink the printing character immediately preceding each printing operation and means acting through a check to press the inking roller into engagement with the printing character with a predetermined force.
2. In a check writer, a type bar having printing characters on one side thereof, a platen bar adapted to press a check into printing contact with one of the characters, an inking roller, and means acting through the check to move the inking roller upwardly and laterally into contact with the printing character immediately preceding each printing action of the platen.
3. In a check writer, a type bar having printing characters on one side thereof, a platen bar adapted to press a check into printing contact with one of the characters, an inking device to ink the printing character immediately preceding each printing action of the bar, a bar having a plurality of parallel rows of sharp points on its upper surface, a matrix plate having a plurality of grooves registering with said rows of sharp points, means to move said sharp pointed bar upward to force a check against said matrix plate to perforate the check, and means to move the matrix plate out of the way of the inking device during the inking operation.
4. In a check writer, a type bar having printing characters on one side thereof, an inking device comprising an ink trough rotatably supporting three contacting rollers, and means to move one of the rollers into inking engagement with one of the printing characters with a predetermined resilient force.
5. In a check writer, a plurality of slidable type bars having printing characters on one side thereof, said bars having longitudinal grooves in their sides adjacent the printing characters, metal spacing plates separating the type bars, and flanges on said plates positioned in said grooves to support and guide the type bars.
6. In a check writer, a slidable type bar having printing characters on one side thereof and a longitudinal groove with ratchet teeth formed therein, a roller adapted to engage the ratchet teeth, an arm upon which the roller is mounted, and resilient means to exert an upward pressure on the arm and roller substantially equal to the weight of the type bar to prevent the accidental stopping of the type bar between printing characters.
7. In a check writer, a type bar having printing characters on one side thereof, a platen bar adapted to press a check into printing engagement with one of the characters, said bar having a longitudinal groove in its bottom, a vertical plate having its upper edge resting in the groove and supporting the bar, said groove being slightly wider than the thickness of the plate to enable the platen bar to rock during a printing action.
8. In a check writer, a slidable type bar having printing characters on one side thereof, a platen bar adapted to press a check into printing engagement with one of the printing characters, a scarifying bar having a plurality of parallel rows of sharp points thereon, a matrix plate having a plurality of grooves registering with said rows of sharp points, screw means to adjust the scarifying bar relative to the platen bar, resilient means normally maintaining said matrix plate in a predetermined normal position, and screw means to vary the normal position of the matrix plate.
9. In a check writing machine, a lower casing, an upper casing, a pair of links hingedly connecting said casings at one end, said links being spaced from the adjacent end of the lower casing and having a projection pivotally connected to the lower part of the lower casing, and a latching device at the other end of the casing, said latching device being in the center of the ends of the casings and clamping said casings together to provide with the hinge connections a three-point even distribution of forces across said casings.
10. In a check writing machine, a plurality of slidable type bars having printing characters on one side thereof, an inking device comprising a trough having inking rollers rotatably mounted therein, means for supporting and guiding a check beneath said type bars, and means beneath and acting against said check to raise the trough to bring one of the inking rollers into contact with the printing characters on the type bars.
11. In a check writing machine, an inclined casing having a plurality of type bars slidably mounted thereon, pawl and ratchet means to hold said bars in various positions of adjustment, a cross bar slidably mounted transversely of the casing, and means to enable the cross bar to be moved longitudinally of the casing to reset the type bars to a predetermined initial position, said cross bar returning by gravity to a position out of the way of the type bars.
12. In a check writing machine, a slidable matrix plate having a plurality of parallel grooves, a scarifying bar having a plurality of parallel rows of sharp points registering with said grooves, means to move the scarifying bar upward against a check to cooperate with the matrix plate to perforate the check, and resilient means to normally maintain the matrix plate in a predetermined position.
13. In a check writing machine, a type bar having printing characters on one side thereof, a platen bar adapted to press a check into printing engagement with one of the characters, said bar having a groove in the bottom thereof, a support for the platen bar, said support being loosely positioned in the groove of the platen bar to enable the platen bar to rock upon the support during a printing action.
14. In a check writer, a type bar having printing characters on one side thereof, a platen bar adapted to press a check upwardly into printing engagement with one of the characters, a support for the platen bar, and means for loosely mounting the platen bar on the support to enable the platen bar to rock transversely of its length during a printing action.
15. In a check writer, a slidable type bar having printing characters on one side thereof, a platen bar adapted to press a check upwardly into printing engagement with one of the printing characters, a scarifying bar adapted to move upwardly to scarify a check, and independent means to adjust the relative positions of the scarifying bar and the platen bar.
